UNITED STATES PATENT OFFICE.

CHARLES W. BESWICK, OF TILTONSVILLE, OHIO.

CLOSET-BOWL.

1,037,110.

Specification of Letters Patent. Patented Aug. 27, 1912.

Application filed June 5, 1911. Serial No. 631,219.

To all whom it may concern:

Be it known that I, CHARLES W. BESWICK, a citizen of the United States, residing at Tiltonsville, in the county of Jefferson and 5 State of Ohio, have invented a new and useful Closet-Bowl, of which the following is a specification:

This invention relates to improvements in closet-bowls of the general type controlled 10 by siphonic action. The invention, however, deals more especially with the initial delivery of the bowl flushing or washing water, with the view of its equable or uniform distribution along the bowl-contour and its 15 upper edge rim.

A further object is to intercept or abate the force or pressure of the water as it is delivered for flushing the bowl regardless of the source or head-pressure.

20 A still further object is to provide for not only washing down or flushing the bowl proper, but also to wash or clean the flushing roll or rim itself well upwardly from its upper surface downwardly toward the bowl.

25 A still further object is to carry out the aforesaid ends, in a simple, expeditious, effective and inexpensive manner.

The invention consists of certain instrumentalities and features substantially as 30 hereinafter fully disclosed and defined by the claims.

In the accompanying drawing illustrating the preferred embodiment of my invention, wherein it will be understood that numerous 35 changes and modifications may be made as relates to the details of the construction and arrangement of the parts without departing from the spirit of the invention,—Figure 1 is a vertical longitudinal section of the closet-bowl; Fig. 2 is a vertical transverse section thereof; Fig. 3 is a fragmentary sectional view more especially of the bowl rim or “roll” in modified form; Fig. 4 is a like 40 view of like parts disclosing another modification.

In putting my invention into practice, I provide the closet-bowl 1 of the well known siphonic action type, or as for that matter of any other make, with a “roll” or rim 2 of 45 the tubular or hollow outline and extending either partly or wholly around the upper edge of the bowl, being integral therewith. This rim-member or “roll” 2, with which 50 communicates the water-inlet or supply-pipe 3, is provided in its bottom close to the inner wall of the bowl with a circular arrange-

ment of closely assembled perforations or openings 4 for suitably delivering or passing the water, received within said “roll” or rim-member, down along the inner surface of the bowl, immediately from the “roll” or rim thus providing for washing down the entire inner wall surface of the bowl proper for the effective removal of all foreign matter therefrom. The “roll” or 60 rim-member 2 has also in its inner annular or circular surface quite near the very upper edge thereof a preferably continuous opening or slot 5 for the further delivery or passing of water, received within said “roll” or 65 rim-member, therefrom, in this case, down upon the roll or rim-member, itself, in broad sheet-form for effecting the removal, or 70 washing off the same, any adhering fecal or other foreign matter.

75 From the foregoing structure, including the “roll” or rim having the double water delivery outlets in the form of the circular arrangement of perforations and the continuous opening or slot, it will be noted that 80 the bowl proper in its entirety, as well as the “roll” or rim, are thoroughly or effectively cleaned of all such matter.

The bowl rim or “roll” 2, which as before stated, is tubular or hollow, has arranged 85 therein a horizontally disposed sub-dividing preferably downwardly curved or concaved member, or septum 6, forming substantially a partition intermediate the upper and lower water outlet points within the rim or “roll” 90 as clearly disclosed in either Fig. 1 or Fig. 2.

In the partition or member 6 about centrally thereof, are numerous perforations or apertures 7, distributed uniformly throughout said partition, for the passage therethrough in the desired manner of the water up into the upper part of the “roll” or rim, whence it is delivered through the outlets 5, 95 into the bowl as aforesaid.

As suggested by Fig. 3 the walls of the 100 delivery slot 5 may be, or rather are, braced or reinforced by the arrangement or formation in connection therewith of struts or partition like portions 8 disposed at suitable intervals throughout the slot preferably as disclosed. Also, as shown in this figure, is a 105 pendent partition or baffle 9 arranged contiguous to, and intermediate the water outlets 5 and the perforations 7 in the partition or member 6, to guard against the casual 110 splashing of the water out through said outlets, especially when under a very heavy

head or pressure of water, thereby controlling the delivery of the water into the bowl. As suggested by Fig. 4, the roll or rim 2 has its upper portion adapted to overhang 5 or overlie the lower portion of, or the roll or rim-proper, as at 10, said overhanging portion terminating inwardly and being spaced off from the inner surface thereof, so as to form a continuous circular delivery 10 or discharging opening or slot 11 corresponding to the above referred to water-delivery opening or slot. The delivery or discharge trend of the opening or slot 11 is preferably downward to cause the issuing 15 sheet of water to follow the contour of the bowl rim or "roll" therebelow for effective washing or cleansing action.

It is clearly apparent from the foregoing disclosure, taken in connection with the accompanying illustration or drawing, that my invention is characterized for great simplicity of structure, embracing the minimum number of parts, therefore inexpensive of manufacture, while it is effective in action 25 for the thorough washing down of the bowl including the washing or cleaning of the bowl rim or "roll", besides being adapted to control the pressure of the inlet-water and to uniformly deliver and distribute the 30 water for cleansing action.

What is claimed:

1. A closet-bowl having a tubular upper-edge "roll" or rim, said rim or "roll" having upper and lower water outlets the lower 35 water-outlet delivering the water for effecting the bowl flushing or washing action, said roll also having a substantially horizontal apertured partition-member intermediate said upper and lower water outlets.
- 40 2. A closet-bowl having an upper-edge tubular "roll" provided with upper and lower water-delivery outlets in its upper and lower inner portions respectively and a substantially horizontal partition-forming 45 member having numerous water delivering perforations therethrough, said partition-forming member being intermediate said upper and lower water outlets.
3. A closet-bowl having an upper-edge 50 tubular roll provided with upper and lower water-delivery outlets in its upper and lower

inner portions, respectively, a partition-forming member having numerous water-delivering perforations therethrough and arranged intermediate said upper and lower 55 water-delivery outlets, and an additional baffle-member depending from the inner upper surface of said roll and having its lower edge spaced off from, and arranged contiguous to said perforated partition. 60

4. A closet-bowl having an upper-edge tubular "roll" provided, intermediate its upper and lower portions with a substantially horizontal perforated partition forming member, said "roll" having a water- 65 outlet in its upper portion, also a baffle-member arranged intermediate said partition and said water-outlet.

5. A closet-bowl having a hollow-roll or rim having an upper water-outlet and a 70 water-inlet, said roll or rim having therein a perforated partition subdividing the same substantially horizontally into upper and lower compartments and arranged intermediate said water-inlet and said water-outlet, 75 said water-inlet providing for delivering the water below said perforated partition and said perforated partition being adapted to serve as a baffle for the water finally delivered through said water-outlet. 80

6. A closet-bowl having an upper-edge tubular member provided with a substantially horizontal perforated partition, said tubular member having a lateral delivery opening formed of opposed spaced-apart 85 portions of said tubular member at its upper portion.

7. A closet-bowl having an upper edge tubular "roll" provided with a substantially horizontal perforated partition, said "roll" 90 having numerous perforations in its bottom and a lateral slot formed of opposed spaced-apart portions of said "roll" at its upper portion.

In testimony that I claim the foregoing 95 as my own, I have hereto affixed my signature in the presence of two witnesses.

CHARLES W. BESWICK.
